UNITED STATES PATENT OFFICE

2,516,655

OSCILLATING WASHING MACHINE TUB

Thomas R. Smith, Newton, Iowa, assignor to The Maytag Company, Newton, Iowa, a corporation of Delaware

Application August 30, 1945, Serial No. 613,547

1 Claim. (Cl. 68—174)

1

The present invention relates to a washing machine consisting of an oscillating tub formed or provided with diametrically opposed baffles so constructed and arranged as to produce a novel washing action for washing clothes.

Among the objects of the present invention is the provision of a novel washing machine tub adapted to be oscillated about a vertical axis. In the disclosed embodiment the tub is formed or provided with a pair of diametrically opposed baffles formed or disposed along the side walls of the tub. These baffles extend radially inward to a rounded point or apex and from this point or apex flare outwardly in a smooth curve merging in an unbroken line with the side walls of the tub.

A further object of the present invention is the provision of a novel tub and baffle arrangement extending along the sides of the tub and for the depth thereof in such manner as to form two opposed pockets, the baffles being so formed as to direct and impel the washing solution and clothes from one into the opposed pocket and by rapidly oscillating the tub, produce a vigorous twisting and bending of the clothes and a highly effective water and washing action.

The invention comprehends such further objects, advantages and capabilities as will later more fully appear and are inherently possessed thereby, and while the drawing shows a preferred embodiment, it is to be understood that the same is susceptible of modification and change, and comprehends other details, arrangements of parts, features and constructions without departing from the spirit of the invention.

In the drawings:

Figure 1 is a view in perspective of the novel washing machine, certain parts being broken away for a more clear disclosure.

Figure 2 is a top plan view of the tub and baffles.

Referring more particularly to the disclosure in the drawings, the embodiment therein selected to illustrate the invention comprises a tub 1 of substantially cylindrical form and having its flat base or bottom 2 mounted upon the upper end of a vertical drive shaft 3 for alternately rotating or oscillating the tub through a desired arc of movement and at a desired speed.

Provided on the interior of the tub are spaced diametrically opposed and imperforate baffles 4, 4 extending substantially vertically along the longitudinal axis of the tub and from the base to the upper part of the tub. As more clearly shown in the horizontal or top plan view of Fig.

5, these baffles extend radially inward to a rounded point or edge 5 and flare outwardly therefrom in a smooth curve at 6, 6 with the base of each baffle merging smoothly into the side walls 7 of the tub to provide a pair of substantially elliptical or kidney-shaped connecting pockets 8, 8.

The vertical drive shaft 3 is preferably journalled adjacent its upper end in a bearing 9 received or press fitted into a sleeve 10 provided at the upper end of a gear case 11 for housing the drive unit. The lower end of the shaft seats upon a thrust bearing 12 and adjacent thereto is journalled in a bearing 13 press fitted into a sleeve or collar 14 formed in the base 15 of the gear case. Slidably and loosely mounted on the shaft is a gear or pinion 16 and directly thereabove a clutch 17 is pinned or keyed to the shaft 3 for oscillating or alternately rotating this shaft 20 when the pinion or gear 16 is clutched thereto.

In continuous meshing engagement with and driving the pinion 16 is a rack 18 slidably mounted and guided upon a cross bar or guide rod 19. The rack is mounted or formed upon the rear of a cross head 20 having a disc 21 provided with a vertically extending slot 22 on its opposite face. In this slot is slidably mounted a collar or slide 23 carried on an eccentric pin affixed to the rear face of a worm wheel 24 which is in continuous 25 meshing engagement with a worm 25 mounted on the shaft 26 of a motor or other power drive 27. Thus by driving and continuously rotating the worm 25 and worm wheel 24, the collar or slide 23 is moved in the vertical slot 22 and thereby reciprocates the cross head 20 and its rack 18. This rack being in continuous mesh with the normally loose pinion 16, oscillates this pinion about the vertical drive shaft 3, and upon elevation of the pinion sufficiently to clutchingly engage the undersurface or clutch face of the clutch 17, the continuously oscillating pinion is clutched to the drive shaft 3 and oscillates the tub through the desired arc and at the desired speed of oscillation. Excellent results have been secured by 40 oscillating the tub of the present embodiment at a speed of approximately 52 oscillations per minute and through an arc of approximately 225 degrees. However, it is to be understood that the speed of oscillation and the arc or angle of movement may be varied somewhat in accordance with the dimensions or capacity of the tub. In the disclosed embodiment, the diameter of the tub is shown as approximately sixteen inches with the two baffles, vanes or blades 4 being of uniform depth and extending into the tub approxi-

45

mately four inches from the outer periphery or substantially one-half the radius of the tub. Also in this form of tub, excellent results were had when employing approximately ten to eleven gallons of washing solution.

The pinion 16 may be raised or lowered by any suitable control means mounted or located at the exterior of the tub and readily accessible to the operator, it being understood that the pinion is of such length as to remain in continuous meshing engagement with the rack at all times. Also, any suitable base, frame or support may be provided for the machine. A suitable lid 28 is provided to form a closure for the tub.

It will be readily apparent from the above de-

scription and the disclosure in the drawings, that the present invention comprehends a novel tub and baffle arrangement and construction. The currents or flow of washing solution carrying the clothes take substantially the path shown by the full line arrows in Figure 2 when the tub is rotating in a counter-clockwise direction, while the arrows in dotted line show the path of washing solution and clothes from one of the elliptical sections when the tub is rotated in a clockwise direction.

Having thus disclosed my invention, I claim:

In a washing machine, a tub therefor mounted for oscillation on a vertical axis and comprising a substantially cylindrical member having a flat base and diametrically opposed imperforate baffles extending radially inward and having a uniform depth of substantially one-half the radius

of the tub, each baffle having its apex extending longitudinally of the tub and with its sides flaring outwardly in a smooth curve merging with the side walls of the tub whereby said baffles divide the tub interior into two substantially elliptical-shaped connecting pockets and when the tub is rapidly oscillated the curved sides of the baffles impel and direct the wash water and clothes carried thereby from each pocket inwardly and into the adjoining pocket and thereby give a vigorous washing action in which the clothes are twisted and manipulated for thorough cleansing, and means for rapidly oscillating the tub through an arc greater than 180°.
